UNITED STATES PATENT OFFICE.

JOHN EDWARDS, OF ALLEGHENY, PENNSYLVANIA, ASSIGNOR OF ONE HALF TO W. V. SHEPPARD, OF ALLEGHENY, PENNSYLVANIA.

RAILWAY-TIE AND RAIL-JOINT.

No 831,270.

Specification of Letters Patent.

Patented Sept. 18, 1906.

Application filed December 30, 1905. Serial No. 293,897.

To all whom it may concern:

Be it known that I, JOHN EDWARDS, a resident of Allegheny, in the county of Allegheny and State of Pennsylvania, have invented a certain new and useful Improvement in Rail-Fasteners, of which the following is a full, clear, and exact description, reference being had to the accompanying drawings, forming part of this specification, in which—

Figure 1 is a side elevation of the railway-tie, showing the rail and a portion of the rail-joint in cross-section. Fig. 2 is a plan view of the same. Fig. 3 is a side elevation of the rail and rail-joint, showing the tie in cross-section. Fig. 4 is a cross-sectional view of the rail, showing the fish-plate in position. Fig. 5 is a perspective view of a portion of the railway-tie, showing one-half of the chair fitted thereon. Fig. 6 is a perspective view of the stop-lug. Fig. 7 is a like view of the locking-lug. Fig. 8 is a vertical sectional view of a modified form of tie and chair. Fig. 9 is a perspective view of the modified form of chair. Fig. 10 is a perspective view of the modified form of locking-lug. Fig. 11 is a side elevation of the rail and chair, the ties being shown in cross-section, in which the chair embraces two ties. Fig. 12 is a perspective view of one-half of this modified form of chair, the ties being shown in dotted lines.

Like symbols of reference indicate like parts wherever they occur.

My invention relates to rail-fasteners; and it consists in devices for securing railroad-rails to the tie, as is hereinafter described.

I will now describe my invention, so that others skilled in the art may manufacture and use the same.

In the drawings, 2 represents the rail, which may be of the ordinary form, and 3 and 3' the chair, which is preferably formed in two parts 3 and 3', and is provided with a flange or shoulder 5, which projects over the foot of the rail when the parts of the chair are in position on the tie 6. Between the seat of the chair and the bottom of the rail is interposed a block of wood 4, which serves as a cushion. The parts 3 3' of the chair, on the outer face of their base, are provided with transverse L-shaped lugs 7, so constructed as to form a recess or slideway for the reception of the flanges 8 of the tie 6. When so formed, the chair is secured to and

fitted on the tie by sliding the parts of the chair on the upper flange of the tie, as is shown in Figs. 3 and 5 of the drawings. This chair is prevented from moving on the tie by the stop-lug 9, which is provided with a projection 10, which passes through a slot in the flange of the tie, and is also provided with a projection 11, which rests on the top of the flange of the tie. The upper portion of this lug rests against the vertical side of the chair 3' and serves as a stop thereto, preventing any spreading of the rails.

The chair is locked in position by the locking-lug 14, which is provided with a projection 12, which passes through a slot in the flange of the tie. It is also provided with a projection 13, which rests on the upper face of the flange of the tie. The shoulder or locking-lug proper, 14, rests against the portion 3 of the chair, and the two parts of the chair are thus held between the lug 9 and the locking-lug 14. As a portion of the chair 3' extends over a portion of the projection 10 of stop-lug, this stop-lug cannot escape from its position in the slot of the tie. The locking-lug 14 may be secured to the tie by means of any suitable key 15 inserted through the eye 15'.

Between the head and foot of the rail 2 is a fish-plate 16, the lower and outer portion of which rests beneath a flange 17 of the chair 3 3', which extends over the flange of the fish-plate. To place these fish-plates in position, they are inserted at the end of the chair and driven into place longitudinally until they come against the stop 18, which is formed at the end of the flanges 17 of the chair 3 3'.

In the use of my improved railway-tie and rail-joint, the tie having been formed of suitable material, preferably of I-bar form, slots having been cut in the flange for the reception of the stop-lug and locking-lug, the tie is placed in position across the line of the railway in the usual manner.

The chairs 3 3' are slipped on the tie, the lug 7 engaging with the flanges of the tie in the manner already described. The stop-lugs are then put in place and the chair is moved back until it comes in contact therewith, so that the chair is in position to prevent the stop-lug from rising, and the stop-lug prevents the chair from slipping out of place. The wooden block 4 and the rail 2 are then placed in the chair, the parts of the

chair are pushed together to engage with and secure the rail, the locking-lug 14 is dropped into its slot and secured by a suitable key, and the fish-plates are driven home under the flanges 17 of the chair.

In some cases the chair will be found to be all that is required, not only to hold the rail to the tie, but to join the rails one with the other, as is shown in Fig. 1. In most cases, however, especially on curves, it is desirable to use the fish-plates above described.

In the foregoing description I have described my tie as adapted to be laid transversely across the line of railway. In Figs. 8 to 10 I have shown a modification of my invention in which the ties are placed parallel to the line of track and the rails are laid longitudinally thereon. In these figures the chair 3^a is shown formed in one piece, having a single shoulder 5^a, and on the opposite side of the rail the key-lug 14^a takes the place of the shoulder, thus enabling the rail to be inserted and removed from its seat in the chair. The remaining parts—that is, the slideways 7^a and the tie 6^a—may be similar to the slideway 7 and tie 6 already described.

Instead of having a single chair 3 for each tie the chair may be made of sufficient length to extend across the space between two ties 30 and to engage with the outer flanges of the ties, as is shown in Figs. 11 and 12. In this modification the slideways 7 are placed at the ends of the chair. To prevent the ties from being drawn toward each other by the jarring of the rail, I employ separators 19, which may be composed of a tube or bar having jaws 20 and stop-nuts 21.

The advantages of my invention result from the construction and arrangement of the

parts, which together form not only a strong, durable, and simple fastening for rails, but also means for joining and uniting the rails to each other.

Having thus described my invention, what I claim, and desire to secure by Letters Patent, is—

1. A rail-fastener consisting of a railway-tie having a flanged head, a chair having slideways adapted to engage with the flanges of the railway-tie, shoulders adapted to engage with the foot of the rail to hold the same within the chair, in combination with a fish-plate adapted to rest on the foot of the rail and bear against the flanges of the chair, the upper portion of the fish-bar being adapted to bear against the under face of the head of the rail, substantially as specified.

2. A rail-fastener consisting of a railway-tie having a flanged head or upper portion, a chair having slideways adapted to engage with the flanges of the tie and having a shoulder adapted to engage with the foot of the rail, and a flange to engage with a fish-plate, substantially as specified.

3. A rail-fastener consisting of a chair having a slideway adapted to engage with the flanges of the tie, having one or more shoulders adapted to engage and hold the foot of the rail, and having a shoulder adapted to retain a fish-plate, and a removable locking-lug; substantially as specified.

In testimony whereof I have hereunto set my hand.

JOHN EDWARDS.
